DUPLICATING MACHINE

James K. Duncan, Chicago, Ill., assignor to Ditto,
Incorporated, Chicago, Ill., a corporation of
West Virginia

Application September 21, 1931, Serial No. 564,025

42 Claims. (Cl. 101—133)

This invention relates to copying machines operating on the hectograph principle and has particular reference to a portable self-contained type of copying machine adapted especially for duplicating menus and similar copying work on a large scale.

An object of the invention is to provide a complete, self-contained, compact and portable copying machine which will be highly efficient in operation by reason of a novel arrangement and cooperation of parts, and which will provide a duplicating unit whereby the production of copying work, such as menus for luncheons, drug stores and dining cars, will be greatly expedited.

10 A further object is to provide a portable copying unit embodying a case with a pivoted hinged cover, the former containing the copying bed and the cover performing the dual function of a closure-means, and a complete impression unit consisting of a platen roller, a paper guide and finger grasping means.

15 A further object is to provide a device of the type described wherein the hinged cover, by its connection to the case or frame, forms a simple means for moving an impression roller over the bed plate, which inherently keeps the roller and paper guide in perfect alignment and eliminates the customary use of slide rods or other more complicated and expensive arrangements for performing the same purpose.

20 A further object is to provide a duplicating device having the duplicating band carried within the frame and the cover being hinged and forming the impression means; the hinged or jack-knife action of the cover offering frictionless and less constrained action in the duplicating operation.

25 A further object is to provide a portable duplicator which will carry a copying roll of considerable length, resulting in extended service and which, through simple winding and stretching means, can be made taut over the bed plate, facilitating the speedy and cleaner removal of the copies.

30 A yet further object is to provide a device as described, having means spacing the roller from the duplicating band, when the cover assumes a spread position to locate the platen at the feeding end of the machine, providing the necessary clearance for the passage of the paper from the guide onto the margin bar.

35 Another object is to provide novel winding and stretching mechanism which, through the manipulation of a single knob, will release the spindles at both ends of the machine, allowing free movement of the band in either direction.

40 A still further object is to provide a portable copying machine as described, with novel means for automatically lifting the impression roller off of impression on the return stroke, while permit-

ting the usual impression during the forward stroke.

45 Another object is to provide a portable copying machine with an automatic paper guide which may form part of the complete unit or constitute an attachment necessitating very little change and expense for installation.

50 Another object is to provide a paper guide for the type of mechanism disclosed, the actuation of which is made possible through the hinged construction of the cover, and which will include means permitting easy regulation of the feeding members in either their upward or downward strokes, thereby making for quick adaptability of the feeder to suit different grades of paper.

55 With these and various other objects in view, the invention may consist of certain novel features of construction and operation, as will be more fully described and particularly pointed out in the specification, drawings and claims appended hereto.

60 In the drawings, which illustrate an embodiment of the device and wherein like reference characters are used to designate like parts—

65 Figure 1 is a perspective view of a copying machine constructed in accordance with the present invention and showing the same in open operative position.

70 Figure 2 is a side view, parts being shown in section, of the copying machine of Figure 1, the cover being shown in closed position.

75 Figure 3 is a detail sectional view taken on the line 3—3 of Figure 2.

80 Figure 4 is a longitudinal sectional view taken substantially through the center of the machine, showing the same in operating position for beginning a printing stroke.

85 Figure 5 is a detail sectional view of the paper guide.

90 Figure 6 is a top plan view of the device of Figure 4, a section of the cover being shown removed.

95 Figure 7 is a transverse sectional view taken on the line 7—7 of Figure 4.

100 Figure 8 is a longitudinal sectional view taken substantially through the center of the machine, showing a modified arrangement for securing the duplicating strips in place.

105 Figure 9 is a transverse sectional view taken on the line 9—9 of Figure 8.

110 Figure 10 is a detail sectional view showing still another modified form of securing means for the duplicating strips.

115 Figure 11 is a side elevational view of a machine provided with means for lifting the impression roller off of impression.

120 Figure 12 is a section taken on the line 12—12 of Figure 11.

125 Figure 13 is a side elevational view showing

a machine of the present invention equipped with paper feeding mechanism.

Figure 14 is a top plan view of the machine shown in Figure 13; and

5 Figure 15 is a fragmentary sectional view showing details of the paper-carrying tray and feeding fingers.

Referring to Figures 1 and 2, the machine is shown as consisting of a case or box-like frame 10 formed of side members 10 and 11, an end member 12 provided with a handle 13 and spring clip 14, a removable end member 15 provided with a retaining clip 16, and a base 17 carrying supporting feet 18 and secured to the end and side members by screws 19. The removable end member 15 is held in place by the retaining clip 16 when the same is positioned as shown in dotted lines in Figure 7, but by means of the securing nut 20 the clip can be turned to permit removal 20 of the member so that access can be had to the interior of the frame. For maintaining the frame in position during the duplicating operation, the supporting feet 18, preferably formed of rubber, are provided with a dished or concaved surface 21 so that the feet will form a suction upon 25 any smooth surface.

The frame provides a bed plate 22 extending transversely of the frame, connecting the side members 10 and 11 and terminating short of the respective end members 12 and 15. The bed plate forms a support for a duplicating bend 23 and is provided with longitudinally extending tracks 24 positioned adjacent the side members and defining the width of the impression roller. 30 At the respective ends of the bed plate are positioned spindles 25 journaled in the side members 10 and 11 and being provided with knurled wheels 26 by means of which the operator can impart rotation to the same to wind or unwind the duplicating band 23 wound on the spindles, respectively. In order to secure a tightening of the duplicating band on the bed plate 22, the spindles at one end are provided with ratchet wheels 27 engaged by the pawls 28 supported for 35 movement in a U-shaped support 29 secured in one of the side members by the nut 30 and being resiliently urged in a downward direction by means of the spring 31. The inwardly directed ends of the respective pawls 28 are secured to the disk 32 non-rotatably mounted on shaft 33, journaled in a side frame and being provided with an operating knob 34. The operating knob is accessible to the operator, and by rotation in either direction the pawls can be 40 withdrawn to release their engagement with the ratchet wheels 27 and thus permit rotation of the spindles. After a fresh portion of the duplicating band 23 has been positioned on the bed plate, the knob 34 is released and, with the pawls in engagement with the ratchet wheels, 45 rotation of the spindle is prevented in a certain direction. However, each spindle can be rotated in the opposite direction to cause a tightening of the band on the bed plate.

50 The cover for the frame, and which also carries the impression means, is formed of two sections 36 and 37, respectively; the pivoted section 36 having depending flanges 38 by means of which the section is pivoted to the frame, the screws 39 (Figure 7) passing through openings in the flanges and being threaded to portions 40 integral with the frame. The reciprocating section 37 is likewise provided with depending flanges 41 and has a hinged connection as at 42 with the section 55 36 and at its other end carries the impression roll-

er 43 journaled in depending lugs 44. At points spaced above the journaling of the impression roller in the depending lugs 44, are provided handles 45 secured to the flanges 41 of the removable section by bolts 46. In reciprocating the impression roller over the gelatin surface, the handles 45 provide grasping means for the operator and facilitate the duplicating operation.

The section 37 of the cover preferably carries the blank sheets of paper to be duplicated, and it is therefore provided with the paper supporting tray, suitably secured to the section and formed of a base 47 and integral spaced strips 48. As clearly shown in Figure 1, the section has a portion cut therefrom and bent downwardly to form a depending flange or paper guide 50, which is slightly dished as at 52 at its center and provided with spaced horizontal extending slots 53 for receiving the paper guides 54. The paper guides are flattened on one side to form guiding edges for the paper and are held in adjusted position in the slots by means of the nuts 55. To complete the hopper through which the sheets of paper are fed to the impression roller, a guard 56 is suitably secured to the lower end of the section 37 and forms a shield to prevent the sheets from coming in contact with the impression roller.

In reciprocating the impression roller 43 over the bed plate, the sections 36 and 37 have a jack-knife action with the section 36 pivoting on the frame, while the reciprocating section 37 has a pivotal relation at 42 with section 36. To limit the spread operative position of the cover, links 57 are pivotally secured at 58 to the flanges 41 of the reciprocating section and, by means of the inclined slot 60 and a pin 61, are operatively connected to section 36. At the projecting end each link is provided with an offset slot 62 which forms a shoulder so that the spread position of the sections is limited unless, by actuation of the link, the pin is caused to enter the offset slot, whereupon the cover can be completely elongated to form a closure means for the frame, as shown in Figure 2.

With the cover in position as shown in Figure 4, it is seen that the impression roller is located 120 on the supporting blocks 63, pivoted at 64 to the respective side frames 10 and 11. The blocks have suitably secured thereto a margin bar 65 having a central cut out portion 66 to permit access to the marginal edge of the paper abutting 125 the bar. By the pivotal construction of the supporting blocks for the margin bar, it will be seen that the bar can be rotated to locate the same in 130 inoperative position. In this position the bar is located in the opening provided in the forward 135 part of the frame, which also functions to receive the impression roller 43 when the cover forms a closure for the frame. The links 57 permit a 140 spread position of the cover to that extent to locate the impression roller 43 on the supporting 145 blocks 63 which locates the margin bar 65 in alignment with the paper guide 50. A sheet of paper from the guide will thus engage the margin bar, the position of which determines the extent of 150 margin on the forward edge of the sheet.

For accommodating strips of a duplicating material, a modified form of machine is shown in Figures 8 and 9, including the usual form of frame comprising side members 10, 11, an end member 12 and a removable end member 68 provided with a handle 69. The frame, in this modification, is constructed to receive a container 70 in which is stored a number of extra gelatin strips 71, the strips being removable to the end adapted to be closed by member 68. At one end of the bed plate

22 is positioned a transverse shaft 72, having projecting from its upper surface a plurality of spaced prongs 73 by means of which the end of the gelatin strip is detachably secured to the shaft 72, non-rotatably positioned in the side frames. At the other end of the bed plate a rotatable shaft 74 is located, also of square cross section, having secured thereto a plurality of spaced prongs 73 for securing the other end of the strip. As this latter shaft is rotatable, means are provided for maintaining the same in adjusted position so that the gelatin strip can be held taut on the bed plate, including a ratchet wheel 75 mounted for engagement with a pawl 76 pivotal-
ly secured to arm 77 non-rotatably mounted on shaft 78. The pawl is supported for movement by the member 79 and is held in engagement with the ratchet wheel by the coil spring 80. Knob 81, secured to the projecting extremity of shaft 78 (Figure 9), permits actuation of arm 77 to withdraw the pawl, releasing engagement of the same with the ratchet wheel and permitting rotation of the shaft 74, which is accomplished by the knurled wheels 82 secured to the respective ends of the same. By the above construction, the strips 71 of gelatinized material can be readily positioned on the bed plate and held in stretched condition to permit easy removal of the duplicated copies by the ratchet and pawl. To remove a duplicating strip, the knob 81 is rotated to withdraw the pawl, releasing its engagement with the ratchet, whereupon the shaft 74 can be rotated and the ends of the strip unlatched from the hooks 73.

In Figure 10 a slightly modified form of the above construction is disclosed, in which the shaft 74 and ratchet 75 are removed and replaced by a plurality of disks 83 positioned adjacent the respective side frames and connected by bar 84. The disks, in turn, are secured to shaft 85 journaled in the side frames, the projecting end of one having suitably secured thereto an operating knob similar to 81. One end of the strip of duplicating material is suitably secured to a non-rotatable shaft, such as 72, secured to the side frames; while the other end is removably fastened to the bar 84 by studs 86. By rotation of shaft 85, through actuation of the operating knob, the bar 84 can be positioned as shown in Figure 10, when the strip of gelatin material will be under maximum tension. A suitable stop is provided to hold the parts in this position, permitting, however, rotation of the disk 83 in a clockwise direction so as to release the tension on the strip to permit removal of the same.

The present invention contemplates automatic feeding mechanism which will function to forcibly eject a sheet of paper toward the margin bar as the cover is located in its maximum operative spread position as shown in Figure 13. The paper supporting tray with which the feeding mechanism is associated, consists of a paper guide 90 supported by and extending between the depending flanges 41 of the reciprocating section 37 of the cover. Positioned against a depending flange on the paper guide is the base portion 91 of spaced strips 92, each strip being provided on its outer side only with an upstanding flange 93 and accommodating at its upper end an adjustable backing member 94. Each strip 92 is provided with a resilient member 95 which serves to maintain the sheets supported by the strips in position so that the feeding fingers, to be presently described, will at all times engage the top sheet. Each strip is also provided with a bent-over flange or lip portion 96 which serves

to maintain the forward edge of the sheets within the tray and allowing separation of the top sheet from the remaining sheets by the feeding mechanism.

The strips 92 are secured in position on the section 37 by means of the triangular shaped supports 97, which are secured at one end to the flanges 93 of the strips and at their other ends to the flanges 41 of the reciprocal section. Journaled in the supports 97 above the paper supporting tray is a shaft 100 on which are non-rotatably mounted elongated feeding fingers 101 adapted to receive a circular rubber band or the like 102, which can be adjusted from time to time to provide the necessary friction for thumbing the sheets of paper. Secured to the respective outer projecting ends of shaft 100 are pinions 103 adapted to have mesh engagement with the gear section 104 suitably journaled to the supports 97 at 105. The lower end of each gear segment has pivotal connection to an operating rod 106 provided with the adjustable stops 107, and having operative connection with section 36 of the cover through means of the bearing 108, which is rotatably mounted on the section and 100 has loose connection with the rod, permitting reciprocating movements of the same.

In operation of the machine to duplicate a sheet fed to the hopper formed by the paper guide 90 and the impression roller guard 56, the impression roller is given a rearward movement toward the right to impress the sheet upon the surface of the gelatin band 23. The forward movement is not initiated until the sheet of paper abuts the margin bar 65 which serves to properly 110 position the forward edge with relation to the gelatin surface, thus determining the margin on the sheet. Actuation of the impression roller in a direction toward the right will cause the respective sections of the cover to approach each other, with the result that the operating rod 106 has movement with respect to the bearing 108 during the reciprocation. Bearing 108 will likewise move toward the right, but since the movement of the left-hand stop 107 is greater in magnitude than that of bearing 108, engagement of the parts will take place when the impression roller has reached its extreme right-hand position on the duplicating surface. This engagement of the left-hand stop 107 with bearing 108 120 causes movement of the operating rods 106 in a direction toward the left, since it will be understood that after engagement takes place continued movement, although to a very slight extent, is imparted to the impression roller; whereupon it completes its rearward printing stroke. Rotation of the gear segments 104 will cause a counter-clockwise rotation to be imparted to shaft 100, and the rotation given to the feeding fingers 101 will cause thumbing of the topmost sheet of paper supported by the paper tray, disengaging its forward edge from the lip 96. The paper is thus held in kinked or separated position with its rear edge in engagement with stop 94, while its mid-portion is held by the feeding fingers 101, as shown in Figure 15.

The parts will remain in the position above described during the return or forward printing stroke of the impression roller, but before the impression roller reaches the end of the stroke, engagement between the bearings 108 and the right-hand stop 107 takes place. Continued movement in a forward direction of the impression roller to locate the same upon the supporting blocks 63, is sufficient to impart the necessary 145

reciprocation to the operating rods 106 to rotate the shaft 100 in a clockwise direction. This rotation of the feeding fingers 101 functions to forcibly eject the separated sheet of paper into the hopper and into engagement with the margin bar 65. This downward movement of the fed sheet of paper is accentuated by the kinked portion of the paper described. It is thus seen that operation of the impression roller in its rearward direction to impress the fed sheet on the duplicating surface, will actuate the feeding mechanism, causing the feeding fingers to separate a sheet from the paper tray; and at the completion of the return or forward movement of the impression roller, the separated sheet is forcibly ejected from the paper tray and caused to be fed so that engagement of its marginal edge with the margin bar is assured.

In Figures 11 and 12 there is disclosed a construction for application to duplicating machines of the type described, whereby the impression roller is automatically lifted off of impression during the return or forward stroke of the cover. This is necessary in machines of this type, since it is customary for the operator to strip the duplicated sheet from the surface of the gelatin band prior to returning the cover for initiating another printing operation. When this procedure is carried out, the impression roller has direct contact with the surface of the gelatin band which will result in smearing one side of the sheet on those copies subsequently duplicated as the roller impresses them on the gelatin surface.

To obviate the above objectionable feature, the present invention contemplates the provision of means, including a yoke, consisting of a journal portion 110 rotatably mounted on the stud shaft 111 fixed to the depending lug 112 integral with the side flange 41 on the section 37, a bearing portion 113 mounting the roller 114, and a handle portion 115 formed integral with the remaining parts and provided with a handle 116. A spring 117 is mounted on the journal portion 110 and has one end fixedly secured to the depending lug, while its other end engages a portion of the yoke to maintain the yoke in a definite position. In this construction, the impression roller 43 is journaled, as usual, at one end in the side flange of the cover, but has its other end mounted in the support 118 provided on the section for the purpose. In operation, to reciprocate the impression roller over the duplicating surface and frame, the operator grasps handle 116 and, by imparting rearward movement to the roller, automatically rotates the yoke on the stud shaft 111. This rotation of the yoke is sufficient to raise roller 114 above the lowermost level of the impression roller so that the latter is permitted to impress the sheet of paper on the duplicating surface. Should the operator strip the duplicator sheet from the band by hand as described, it will be seen that during the return movement of the impression roller, contact between the same and the duplicating band is prevented. In order to impart forward movement, or movement toward the left in Figure 11, to the impression roller, it is necessary for the operator to automatically rock the yoke on the stud shaft 111 in a counterclockwise direction, thus locating the roller 114 in its extreme lower position. In assuming this position, the roller 114 engages the track 24 formed on the frame and thus functions to lift the impression roller from contact with the gelatin surface. The yoke is held in the position described during the entire forward movement of the impression roller; and

since the roller is not permitted to contact the gelatin band, the surface of the same is kept clean and in condition for again impressing a sheet upon the gelatin band.

From the above, it will be seen that the present invention, among other features, contemplates the provision of a compact and portable duplicating unit in which the frame carries the flat duplicating surface and has a cover of articulated sections jointly pivoted at one end and, with inter-linking members, performs the dual function of actuating members for moving an impression roller over the duplicating surface and as a closure means for the frame. The fixed and permanent relation between the paper guide, impression roller and actuating members makes for less inconvenience and trouble and better work by inexperienced hands; and by the absence of any sliding action between the parts, little lubrication is required, with all the parts practically operating in a frictionless manner. The hinged cover with substantial jointed construction between the sections, together with the slotted link and pin construction, provides aligning features for the impression roller which offer a greater freedom and more frictionless operation, with the additional advantage whereby the impression roller is received in the frame when the cover is closed, making it possible to present a compact appearance resulting in a readily handled article.

It is to be understood that the invention is not limited to the exact embodiment of the device shown, as various and other forms of the device will be apparent to those skilled in the art without departing from the spirit of the invention or scope of the claims.

What is claimed is:

1. A duplicating machine, comprising, in combination, a base providing a flat duplicating surface, and a hinged cover pivoted to the base and carrying impression means at its free end.

2. A duplicating machine, comprising, in combination, a base providing a flat duplicating surface, and a two-part hinged cover pivoted to the base at one end and carrying impression means at its other end.

3. A duplicating machine including, in combination, a base providing a flat duplicating surface, and a cover having a hinged connection intermediate its ends, one end being pivoted to the base and its other end carrying impression means, whereby the articulated sections of the cover permits movement of the impression means over the duplicating surface.

4. A duplicating machine including, in combination, a base providing a flat duplicating surface, and a cover having a hinged connection intermediate its ends, one end being pivoted to the base and its other end carrying impression means, whereby the articulated sections of the cover permits movement of the impression means over the duplicating surface, the cover also forming closure means for the base.

5. A duplicating machine including, in combination, a base formed of a box-like frame providing a bed plate, a duplicating surface supported by said bed plate, and a cover formed of articulated sections having one end pivoted to the base and its other end carrying impression means.

6. In a duplicating machine, in combination, a base providing a flat duplicating surface, and a cover formed of articulated sections and carrying impression means.

7. A duplicating machine including, in combination, a base formed of a box-like frame pro-

- viding a bed plate, spindles journaled in said frame, a duplicating band wound on said spindles and having a portion supported by said plate, and a cover for the frame formed of articulated sections, one end being pivoted to the base and its other end carrying impression means including a platen roller, said cover permitting movement of the roller over the duplicating band.
8. A duplicating machine including, in combination, a base formed of a box-like frame providing a bed plate, spindles journaled in said frame, a duplicating band wound on said spindles and having a portion supported by said plate, and a cover for the frame formed of articulated sections, one end being pivoted to the base and its other end carrying impression means including a platen roller, said cover permitting movement of the roller over the duplicating band and being also adapted to form a closure for the frame.
9. A duplicating machine including, in combination, a base formed of a box-like frame providing a bed plate, spindles journaled in said frame, a duplicating band having a portion supported by the bed plate and its ends wound on the spindles, means for maintaining the portion on the plate taut, a cover for the frame formed of hinged sections, one section being pivoted to the frame, the other section having journaled therein a roller, and a paper guide formed in said last-mentioned section, whereby said cover is adapted to be actuated to reciprocate the impression roller over the bed plate.
10. A duplicating machine including, in combination, a base formed of a box-like frame providing a bed plate, a duplicating surface provided by the bed plate, and a cover for the frame formed of hinged sections, one of which is pivoted to the frame, the other carrying an impression roller, whereby said cover is operative to reciprocate the impression roller over the duplicating surface, said cover also forming closure means for the frame, the frame providing a receptacle for the roller when the cover is in closed position.
11. A duplicating machine, in combination, a box-like frame having a removable end member, a bed plate provided by said frame, a duplicating surface for the plate positioned by access through the end closed by said removable member, and a cover for the frame, said cover carrying impression means.
12. A duplicating machine including, in combination, a base formed of a box-like frame, a bed plate provided by said frame, a duplicating surface supported by said plate, a cover formed of hinged sections, one of which is pivoted to the frame, the other having journaled therein an impression roller for reciprocation over the duplicating surface, and means operatively associated with the roller for automatically raising said roller off of the duplicating surface in one direction of reciprocation.
13. A duplicating machine including, in combination, a base formed of a box-like frame, a bed plate provided by said frame, a duplicating surface supported by said plate, a cover formed of hinged sections, one of which is pivoted to the frame, the other having journaled therein an impression roller for reciprocation over the duplicating surface, and means journaled in said last-mentioned section and adapted to be actuated by the operator during reciprocation of the impression roller, said means operating to automatically raise the roller off of impression during one direction of reciprocation.
14. In a duplicating machine, a frame providing a flat duplicating surface, a roller forming impression means adapted to reciprocate over the surface, means carrying a paper guide journaling said roller, said means also journaling a yoke member, a second roller carried by said yoke, and a handle secured to the yoke, whereby said second roller is depressed when the handle is rocked to cause return movement of the impression means.
15. In a duplicating machine, in combination, a frame providing a flat duplicating surface, a cover for the frame formed of hinged sections, one of which is pivoted to the frame, the other carrying an impression roller, a paper tray also carried by said last-mentioned section, and paper feeding means rotatably mounted in said tray, said means including a shaft having feeding fingers thereon, and an operating rod for rotating said shaft.
16. In a duplicating machine, in combination, a frame providing a flat duplicating surface, a cover for the frame formed of hinged sections, one of which is pivoted to the frame, the other being reciprocable and carrying an impression roller, a paper tray secured to the reciprocable section, and paper feeding means journaled in said tray, said means including a shaft carrying feeding fingers and an operating rod for rotating said shaft having stops thereon and being supported on the pivoted section of the cover.
17. In a duplicating machine, a frame providing a flat duplicating surface, a cover for the frame formed of hinged sections, one of which is pivoted to the frame, the other being reciprocable and carrying an impression roller, a paper carrying tray mounted on said reciprocable section, and paper feeding means for feeding the top sheet to the impression means at the completion of a printing stroke.
18. In a duplicating machine, a frame providing a flat duplicating surface, a cover for the frame formed of hinged sections, one of which is pivoted to the frame, the other being reciprocable and carrying an impression roller, a paper carrying tray mounted on said reciprocable section, and paper feeding means for feeding the top sheet to the impression means, said means being actuated by the jack-knife action of the cover to cause feeding at the completion of a printing stroke.
19. In a duplicating machine, a frame providing a flat duplicating surface, a cover for the frame formed of hinged sections, one of which is pivoted to the frame, the other being reciprocable and carrying an impression roller, a paper carrying tray mounted on said reciprocable section, and paper feeding means for feeding the top sheet to the impression means including rotatable feeding fingers and an operating rod to rotate said fingers, said rod being actuated by the movement of the reciprocable section.
20. In a duplicating machine, a frame providing a flat duplicating surface, a cover for the frame formed of hinged sections, one of which is pivoted to the frame, the other being reciprocable and carrying an impression roller, a paper carrying tray mounted on said reciprocable section, and paper feeding means for feeding the top sheet to the impression means including rotatable feeding fingers, an operating rod to rotate said fingers, and stops on said rod for engaging the bearing supporting the rod on the pivoted section, whereby said rod is actuated by the movement of the sections of the cover.

21. A duplicating machine, in combination, a frame providing a flat duplicating surface, a cover therefor having hinged sections and being pivoted to the frame, an impression roller carried by said cover and adapted to be reciprocated over the duplicating surface, a paper tray secured to one hinged section of the cover, and paper feeding means operated by the movement of one section of the cover with respect to the other section. 5 80
22. A duplicating machine, in combination, a frame providing a flat duplicating surface, a cover therefor having hinged sections and being pivoted to the frame, an impression roller carried by said cover and adapted to be reciprocated over the duplicating surface, a paper tray secured to one hinged section of the cover, and paper feeding means including rotatable fingers and an operating rod, said rod being reciprocated by the movement of one section of the cover with respect to the other section. 10 85
23. A duplicating machine embodying a plurality of hinged sections carrying an impression roller, and paper feeding means adapted to feed a sheet of paper to the roller, including thumbing fingers actuated by movement of one section relative to the other. 15 90
24. A duplicating machine embodying a plurality of hinged sections, a frame to which one section is pivoted, an impression roller carried by another of said sections, whereby said roller is reciprocable over the frame, and paper feeding means actuated by the hinged action of the sections during reciprocation of the roller to feed a sheet of paper to the roller at the completion 20 95
- 35 of a printing operation. 105
25. A duplicating machine embodying a plurality of hinged sections, a frame to which one section is pivoted, an impression roller carried by another of said sections, whereby said roller is reciprocable over the frame to complete a duplicating operation, and a depending flange provided on the second-mentioned section forming a paper guide to direct sheets of paper to the roller. 40 110
26. A duplicating machine, in combination, a frame providing a duplicating surface, a cover for the frame formed of two members, one pivoted to the frame and the other pivoted to the free end of the first mentioned member, the second 45 115
- 50 mentioned member carrying an impression roller, and means limiting the spread position of the members to retain the roller in contact with the duplicating surface including a link connecting the members intermediate their ends. 120
27. A duplicating machine, in combination, a frame providing a duplicating surface, a cover for the frame formed by two members, one pivoted to the frame and the other pivoted to the free end of the first mentioned member, the second 55 125
- 60 mentioned member carrying an impression roller, and means limiting the spread position of the members to retain the roller in contact with the duplicating surface including a link pivoted to one member and slidably connecting with the other member. 130
28. In a duplicating machine, a box-like frame, a member carried by said frame and provided with a duplicating surface, a closure member for 70 135

- 70 145
- 75 150
- thereto, and an impression roller carried by said closure member and movable therewith to press a sheet of paper against said duplicating surface. 29. In a duplicating machine, a box-like frame, a member carried by said frame and provided with a duplicating surface, a closure member for
- said box-like frame and movable with respect thereto, and an impression roller, said impression roller having its axis of rotation fixed with respect to the closure member and being adapted to be moved over the duplicating surface by movement of said closure member. 30. In a duplicating machine, a box-like frame, a member carried by this frame and provided with a duplicating surface, a closure member for said box-like member, and an impression roller rotatably journaled adjacent a portion of the closure member, the axis of rotation of said roller being fixed with respect to said portion of said closure member, said closure member being movable with respect to said frame to draw said impression roller over said duplicating surface. 31. In a duplicating machine, a box-like frame, a member carried by said frame and provided with a duplicating surface, a closure member for said box-like frame and movable with respect thereto, an impression roller carried by said closure member and movable therewith to press a sheet of paper against said duplicating surface, and means responsive to movement of said closure member for feeding sheets of paper to said impression roller. 32. A duplicating machine, a box-like frame, a member carried by said frame and provided with a duplicating surface, a closure member for said box-like frame and movable with respect thereto, an impression roller, said impression roller having its axis of rotation fixed with respect to the closure member and being adapted to be moved over the duplicating surface by movement of said closure member, and means carried by said closure member and responsive to the movement thereof for feeding paper to said impression roller. 33. In a duplicating machine, a box-like frame, a member carried by said frame and provided with a duplicating surface, a closure member for said box-like member, an impression roller rotatably journaled adjacent a portion of the closure member, the axis of rotation of said roller being fixed with respect to said portion of said closure member, said closure member being movable with respect to said frame to draw said impression roller over said duplicating surface, and means carried by said closure member and responsive to the movement thereof to feed paper to said impression roller. 34. In a duplicating machine, a box-like frame, a member carried by said frame and provided with a duplicating surface, a closure member for said box-like frame and movable with respect thereto, an impression roller carried by said closure member and movable therewith in one direction to press a sheet of paper against said duplicating surface, and means for displacing said impression roller away from said duplicating surface when the closure member is moved in the other direction. 35. In a duplicating machine, a box-like frame, a member carried by said frame and provided with a duplicating surface, a closure member for said box-like frame and movable with respect thereto, an impression roller, said impression roller having its axis of rotation fixed with respect to the closure member and being adapted to be reciprocated over the duplicating surface by movement of said closure member, and means for displacing said impression roller away from said duplicating surface during alternate strokes thereof. 36. In a duplicating machine, a box-like frame,

- 40 a member carried by said frame and provided with a duplicating surface, a closure member for said box-like member, an impression roller rotatably journaled adjacent a portion of the closure member, the axis of rotation of said roller being fixed with respect to said portion of said closure member, said closure member being reciprocable with respect to said frame to draw said impression roller over said duplicating surface, and means for displacing said impression roller away from said duplicating surface during movement of said closure member in one direction. 80
- 45 37. In a duplicating machine, a frame, a platen carried by the frame and provided with a duplicating surface, a cover-member having one end pivoted to the frame, a second member pivoted to the free end of the first mentioned member, and an impression roller carried by said second member and movable therewith over said duplicating surface, the axis of rotation of said impression roller being fixed with respect to said second member. 90
- 50 38. In a duplicating machine, a frame, a platen carried by the frame and provided with a duplicating surface, a member having one end pivoted to the frame, a second member pivoted to the free end of the first mentioned member, an impression roller carried by said second member and movable therewith over said duplicating surface, the axis of rotation of said impression roller being fixed with respect to said second member, and means responsive to the movement of said second member for feeding sheets of paper to said impression roller. 95
- 55 39. In a duplicating machine, a frame, a platen carried by the frame and provided with a duplicating surface, a cover-member having one end pivoted to the frame, a second member pivoted to the free end of the first mentioned member, an impression roller carried by said second member and movable therewith over said duplicating surface, the axis of rotation of said impression roller being fixed with respect to said second member, and means for displacing said impression roller away from said duplicating surface during movement of said closure member in one direction. 100
- 60 40. In a duplicating machine, a frame, a platen member carried by the frame and provided with a duplicating surface, foldable cover-means connected to the frame adjacent one end of said platen, and an impression roller carried by said foldable means and movable thereby over the duplicating surface. 105
- 65 41. In a duplicating machine, a frame, a platen member carried by the frame and provided with a duplicating surface, foldable means connected to the frame adjacent one end of said platen, an impression roller carried by said foldable means and movable thereby over said duplicating surface, and means responsive to movement of said foldable means to feed sheets of paper to said impression roller. 110
- 70 42. A duplicating machine comprising a frame, a flat platen in said frame for holding a duplicating master, a member pivoted adjacent one end of said platen, the pivotal axis of said member extending transversely of said platen, a second member pivoted to the free end of the first-mentioned member, an impression roller rotatably carried by said second member and movable longitudinally of said platen, and means mounted on said second member for guiding sheets of paper to said roller. 115
